ELECTROLYTIC CONDENSER

Willem Frederik Straub and Hendricus Johannes Lemmens, Eindhoven, Netherlands, assignors to Radio Corporation of America, a corporation of Delaware

Application February 11, 1932, Serial No. 592,252
In Germany February 13, 1931

3 Claims. (Cl. 175—315)

The invention relates to an electrolytic condenser in which the various plate-shaped electrodes or the various successive turns of a single electrode are arranged at some distance from 5 one another and are separated by an intermediate layer. In fact, the condenser plates of electrolytic condensers are frequently rolled up in order to save space. The intermediate layer whereby the windings of the electrodes are spaced 10 apart from one another consists in many cases of an absorbing substance containing the electrolyte, for example, of asbestos or paper.

It has been found that in this case undesirable phenomena may occur due to the fact that gases 15 are developed in the electrolyte and that the intermediate layer, which is in contact with the electrodes, prevents the gas bubbles from ascending. At the point at which gas bubbles remain behind between the electrode and the intermediate 20 layer the electrode will be corroded which results in a considerable decrease of the length of life of the condenser.

According to the invention this drawback is removed by having the various electrodes or the 25 successive turns of one electrode separated from one another by spacing members whereby paths are left free for the ascent of gas bubbles.

Said spacing members may be formed, for example, by rods of insulating material such as 30 glass.

In another suitable embodiment the spacing member consists of an undulated or profiled plate of insulating material, for example, of paper or celluloid. More particularly if the condenser 35 consists of two parallel wound plates separated from one another by spacing member which does not pass the electric current or only to a slight extent, such as celluloid, it is important to perforate said spacing member. The transmissibility for the electric current may be still further improved by drawing one or more wires of insulating material through the perforations of the spacing member, said wires running alternately on either side of the spacing member in 40 such manner however that they do not come into contact with the electrodes.

The invention will be explained more fully with reference to the accompanying drawing, in which,

50 Fig. 1 represents schematically a lateral elevation of a condenser according to the invention;

Figures 2 and 3 represent sections of different forms of execution taken on the line II—II of Figure 1; and,

Fig. 4 represents a detail of another form of execution.

The construction according to the invention is of great importance with condensers whose electrodes consist entirely or partly of one of the 5 metals of the first sub-group of the fourth principal group of the periodic system of the elements and which are coated with a layer of an oxide of these metals.

Referring to Figure 2, a condenser vessel 1, which simultaneously acts as one of the electrodes, consists, for example, of iron whereas a rolled up electrode 2 consists of zirconium coated with a layer of zirconium oxide. Said vessel is filled with a solution of potassium hydroxide. 15 The successive turns of the electrode 2 are spaced apart by one or more undulated strips 3 of celluloid or other suitable substance.

The fact that the bottom of the vessel 1 also consists of iron warrants a sufficient electrical 20 conductivity between the two electrodes.

As shown in Fig. 1 the terminal 4 of the condenser is directly connected to the iron vessel 1 and the metallic strip 5 for the connection of the electrode 2 passes through the cover of the condenser.

Fig. 3 represents two electrodes 2 and 6 rolled up in parallel and consisting, for example, of titanium coated with a layer of titanium oxide. In this case the spacing members are formed by 30 glass rods 7 extending in the longitudinal direction of the condenser. The vessel 8 consists in this case, for example, of ebonite or of an artificial resin with a filling material, such, for example, as that known under the registered trademark philite. The rods 7, too, may be made of this material if desired. It is evident that in the embodiments shown in Figures 1 and 2 gas bubbles have an ample opportunity of ascending in 35 the electrolyte.

If in the construction of Figure 3 instead of the rods 7 use would be made of a rolled-up undulated plate of celluloid or other insulating material which does not take up liquids and which consequently does not become conductive, the 40 resistance of the condenser would be considerably increased.

Said drawback may be overcome in this case by taking care that apertures are left free in the celluloid, for example, by perforating the latter. 50

Fig. 4 represents a portion of two condenser plates 2 and 6 between which such a perforated strip 3 of celluloid is arranged. The portion of this strip on the left-hand side of the line IV, IV is shown in section. Through the holes is laced 55

a copper wire 9 which brings the spaces to the left and the right of the celluloid strip into connection with one another.

It is evident that several variations are possible 5 without departing from the principle of the invention.

The condensers described with reference to Figs. 3 and 4 are alternating current condensers.

Those shown in Figs. 1 and 2 are destined for 10 smoothing pulsatory direct currents. If in the condensers according to Figs. 3 and 4 a metal plate without oxide film, for example, a nickel plate is substituted for one of the titanium plates, one obtains a condenser having a slight 15 internal resistance and suitable for smoothing a pulsatory direct current.

We claim:

1. In an electrolytic condenser, a compact roll composed of at least two electrode sheets and 20 an undulated strip of insulation material said strip being interposed between the two sheets so as to separate same, a container for said roll and an electrolyte solution within the container adapted to fill the spaces therein, said compact roll 25 being immersed in said solution, and means for determining the internal resistance of the condenser comprising at least one conductive strip supported by and passing through said strip at several points for bringing the electrolyte on 30 either side of the strip into conductive relationship.

2. In an electrolytic condenser, a compact roll composed of at least two electrode sheets and an undulated strip of insulation material interposed between the two rolled sheets so as to maintain each sheet separate from the other along its entire 5 surface, a container for said roll and an electrolyte solution within the container into which said roll is immersed said electrolyte solution being adapted to fill all of the spaces within the container, said strip of insulation material having 10 perforations therein and a conducting strip inserted through said perforations.

3. In an electrolytic condenser a compact roll composed of at least two electrode sheets and an undulated strip of insulation material between 15 the two sheets arranged so as to separate one of the sheets from the other, a container and an electrolyte solution within which the compact roll is immersed, means for adjusting the internal resistance of the unit comprising means having 20 a substantially high electrical conductivity arranged so as to form a low resistance path between the electrolyte on one side of the insulation material and the electrolyte on the other side thereof to thereby reduce the resistance of portions of the path and at the same time reduce the length of the electrical path between various 25 points of the two electrodes.

WILLEM FREDERIK STRAUB. 30
HENDRICUS JOHANNES LEMMENS.
